CLAIM

The ornamental design for an applicator suppository injector, as shown and described.

DESCRIPTION

FIG. 1 is a perspective view of an applicator suppository injector showing my new design;

FIG. 2 is a front elevation view, the rear elevation view being the same image thereof;

FIG. 3 is a side elevation view, the opposite side being the same image thereof;

FIG. 4 is a top view thereof; and,

FIG. 5 is a bottom view thereof.
